United States Patent Office

Des. 198,164
Patented May 12, 1964

198,164

MOBILE TELEPHONE CONTROL UNIT

Henry Dreyfuss, South Pasadena, Calif., assignor to Bell
Telephone Laboratories, Incorporated, New York, N.Y.,
a corporation of New York

Filed Dec. 24, 1963, Ser. No. 77,914

Term of patent 14 years

(Cl. D26—14)

FIG. 1

FIG. 2

FIG. 3

FIG. 4

FIG. 1 is a left front perspective view of a mobile telephone control unit showing my new design;

FIG. 2 is a right front perspective view of a mobile telephone control unit showing my new design;

FIG. 3 is a side elevation view; and

FIG. 4 is a bottom view thereof.

The dominant features of my new design reside in the portion shown in solid lines on the drawing.

I claim:

The ornamental design for a mobile telephone control unit, as shown and described.
